COMBINATION TRAY AND DOOR BOLT

William H. Brown, Cleveland, Ohio

Application October 12, 1934, Serial No. 748,131

6 Claims. (Cl. 292—57)

It is well known that women quite frequently have their rings and other jewelry stolen by inadvertently leaving them in a washroom, after having removed the jewelry to facilitate bathing.

- 5 It is the object of my invention to provide a jewelry tray or receptacle that will be so associated with the bolting or locking of the washroom door that if the woman will take the trouble to place her removed jewelry in the tray after she 10 bolts or locks the door, she will be likely to be reminded to repossess herself of the jewelry before she is able to unbolt the door for egress from the washroom.

Referring to the drawing annexed,

- 15 Fig. 1 is a perspective view of a preferred form of my device applied to a door-way;

Fig. 2 is a vertical sectional view thereof; and

Fig. 3 is a front view thereof with the jewelry tray down, in non-used position.

- 20 Referring to the drawing by reference characters, 5 designates a bolt-support consisting of a flat plate adapted to be fastened to the inner face of the door by the several screws 6, this plate being provided at each end with a forwardly extending arm 7 in which is slidably and rotatably mounted a bolt 8. Affixed rigidly to this bolt at a point between the arms 7 is the inner edge of a tray 9. Each one of the arms 7 is provided with a tray-supporting lug 10 which extends inwardly towards the adjacent edge of the tray.

The tray is made narrower than the distance between the two supporting lugs 10, so that when the tray is not resting on either one of these lugs, 35 it will gravitate or swing down to a vertical position in parallelism with the inner face of the door, as shown particularly in Fig. 2. The bolt 8 is long enough to project laterally beyond both arms 7, so that either end of the bolt may be used as a lock or bolt. The main support 5 is affixed to the door at a point where one projecting end of the bolt, when slid outwardly by a lateral movement of the tray 9, which is used as a sort of handle for this purpose, said projecting end of the bolt will engage a keeper 11 affixed to an adjacent part of the door frame, in line with the bolt.

It will be observed that when the door is closed and the tray is raised to a point above the lugs 50 10 and is moved laterally toward the keeper, the bolt will slide in the holes in the arm 7 and be engaged with the keeper 11, whereupon the tray may be released and allowed to gravitate to a resting point on the adjacent supporting lug 10. The tray will then be in a position to re-

ceive the rings and other jewelry, and since it will be impossible to unlock the door without taking hold of the tray to withdraw the bolt, the occupant of the room will be likely to be reminded of the jewelry upon the tray, or be forced to dump the jewelry upon the floor at her feet. It will thus be observed that if the occupant of the room opens the door from the inside and has been careful to previously place her jewelry upon the tray, there will be practically no chance of 10 her forgetting to gather up her jewelry before she leaves the room.

Duplication of the bolt extension and the tray-support 10 renders the device applicable to a left-swinging door or a right-swinging door, as is 15 obvious.

In order to prevent the bolt being slid into locking position without first lifting the tray to article-holding position, I provide guard fingers 10' which are desirably formed by extensions of 20 the tray-support bars 10, these extensions being turned backwardly parallel with the arms 7 and terminated at a point under the bolt. With these guard members 10', it will be seen that the bolt and its tray can have no appreciable sliding action until the tray is lifted to a point above the lugs 10 and guards 10', whereupon the tray and the bolt may be moved to locking positions. This obviously renders the device fool-proof.

It will be understood of course that my device 30 may be used with advantage in connection with rooms or booths other than washrooms, and that the article-holding member 9 may be sufficiently capacious to hold articles other than jewelry, as for instance, purses, small handbags, etc. 35

I claim:

1. A device of the class described embodying a slidable and rotatable door bolt and a support therefor, the support being adapted to be attached to the inner face of the door, said support being 40 provided with a tray-support, and a tray attached to said bolt and adapted to slide and rotate with it and to rest upon said tray-support when the bolt is in locking position and to be disconnected therefrom when the bolt is in non-locking 45 position to thereby support the tray in use-position when the door is bolted and to permit it to assume a non-use or dumping position when the bolt is moved to non-locking position.

2. A device of the type set forth embodying 50 a main support adapted to be attached to a door and provided with a tray-support, a slidable and rotatable bolt mounted in said main support, and a tray affixed to said bolt and adapted to slide and rotate with it so that the tray may be raised 55

and laterally moved into engagement with the tray-support when the bolt is moved to locking position.

3. In a device of the class described, a door-locking element having associated with it an article-holding member normally tending to dump and a device for supporting the article-holding member in use-position when the locking element is moved to locking position and to release said article-holding member when the locking element is moved to unlocking position.

4. The structure recited in claim 3, the locking element consisting of a slideable bolt and the article-holding member consisting of a tray-like member affixed to and adapted to slide with said bolt.

5. A device of the class described embodying a slideable and rotatable door bolt and a support therefor, the support being adapted to be attached to the inner face of the door, said support being provided with a tray-support, and a tray attached to said bolt and adapted to slide and rotate with it and to rest upon said tray-support when the bolt is in locking position and to be disconnected therefrom when the bolt is in non-locking position to thereby support the tray in use-position when the door is bolted and to permit it to assume a non-use position when the bolt is moved

to non-locking position, the ends of the bolt being extended beyond the support at both ends thereof and one of the tray-supports being located at each end of the device to thereby adapt the device for use on left-swinging doors as well as upon right-swinging doors.

6. A device of the class described, embodying a slideable and rotatable door bolt and a support therefor, the support being adapted to be attached to the inner face of the door, said support being provided with a tray-support, and a tray attached to said bolt and adapted to slide and rotate with it and to rest upon said tray-support when the bolt is in locking position and to be disconnected therefrom when the bolt is in non-locking position to thereby support the tray in use-position when the door is bolted and to permit it to assume a non-use position when the bolt is moved to non-locking position, the ends of the bolt being extended beyond the support at both ends thereof and one of the tray-supports being located at each end of the device to thereby adapt the device for use on left-swinging doors as well as upon right-swinging doors.

WILLIAM H. BROWN.
